UNITED STATES PATENT OFFICE.

RUDOLPH SATTLER, OF CINCINNATI, OHIO, AND LEO J. MORAND, OF COVINGTON,
KENTUCKY.

INKING APPARATUS.

1,191,837.

Specification of Letters Patent.

Patented July 18, 1916.

Application filed October 29, 1914. Serial No. 869,329.

To all whom it may concern:

Be it known that we, RUDOLPH SATTLER and LEO J. MORAND, citizens of the United States, and residents of Cincinnati, in the county of Hamilton and State of Ohio, and Covington, in the county of Kenton and State of Kentucky, respectively, have invented certain new and useful Improvements in Inking Apparatus, of which the following is a specification.

Our invention relates to inking apparatus for printing presses, and more especially for embossing presses; and the object is to reduce the waste of ink incident to the wiping of the surface of the embossing die, as well as to reduce the waste of paper or other material used in the process of wiping said surface.

Our invention consists in the parts and in 20 the details of construction and arrangement of parts as will hereinafter be more fully described and claimed.

In the drawings: Figure 1 is a general perspective view of an embossing press having our invention applied thereto; Fig. 2 is a side elevation of the same, the lower part of the press being omitted; Fig. 3 is a cross section of the blade; Fig. 4 is a cross section of a modified blade; Fig. 5 is a plan view, on an enlarged scale, of our invention, omitting the liquid-supply tank and connections; Fig. 6 is a rear elevation of the same; Fig. 7 is a side elevation of the same; Fig. 8 is a vertical cross section on the line $w-w$ of Fig. 6; Fig. 9 is a plan view of a modified pressure bar also showing the blade and parts of the housing; Fig. 10 is a rear elevation of the same; Fig. 11 is a vertical cross section on the line $x-x$ of Fig. 10, omitting the part 30 of the housing; Fig. 12 is a vertical cross section on the line $y-y$ of Fig. 14; Fig. 13 is a vertical cross section on the line $z-z$ of Fig. 15; Fig. 14 is a plan view of a pressure bar similar to that shown in Figs. 5 to 8, inclusive, but showing a modification of the adjustment; Fig. 15 is a plan view similar to Fig. 9, showing a further modification of this pressure bar similar to that of Fig. 14; Fig. 16 is a partial vertical longitudinal section, further enlarged, on the line $m-m$ of Fig. 17, more clearly illustrating the clutch; and Fig. 17 is a vertical cross section, on a similar scale, on a line $n-n$ of Fig. 16.

The press which we have chosen for illus-

trating the use of our invention has the embossing die 1 reciprocated by a lever 2 through the medium of links 3 and 4, back toward the fountain 5 and forward to the front of the press, where the impression is made. The fountain 5 has the roller 6 taking up ink 7 from the fountain, with a doctor roller 8 bearing thereon; and a distributing roller 9, suitably carried on an arm 10, takes the ink from the roller 6 and distributes it over the die 1 when the die is back 65 near the fountain. The ink is thus spread over the entire surface of the die and down in the depressions made by the engraving on the die, such as the depressions 11 therein, but only the ink in the depressions is to 70 be transferred to the work, as is well known in the art of embossing and printing with one impression. Therefore, a means is provided for wiping all of the ink from the die except that in the depressions 11. On 75 this press, a pad 12 with a tightly stretched surface of suitable fabric 13, such as felt, has a web of paper 14 drawn under it, so that, as the die 1 passes under the pad 12, the upper surface of the die and the lower 80 surface of the web 14 are very tightly pressed together and all of the ink on the plane surface of the die is wiped off onto the web 14, and carried away, as film of ink spread across the surface of the web. This 85 web of paper 14 is usually supplied from a roll 15 passing forward over a roller 16 and down between rollers 17 and 18, and then forward and down over a roller 19 to the pad 12, and back under the pad 12 to a roll 90 20 upon which the paper is wound. The roller 17 is intermittently turned by suitable mechanism, which need not be described herein.

As here shown in connection with the 95 press above described, housings 21 and 22 are clamped to a cross bar or strut 23 which the press has at the rear, and these housings have, at their rear ends, bearings for an upper roller 24 and a lower roller 25, and, immediately forward thereof, support a pressure bar 26 and a blade 27 under the pressure bar, while immediately forward of the clamping means of the housing they support a trough 28 and bearings for a roller 28' 100 adapted to turn in the trough. Near the top of the press, just in front of the roll 15, is a roller 29. With these parts thus pro-

vided, the stretch of the web from the part 12 back to the roll 20 is passed over the roller 28', between the pressure bar 26 and blade 27, under the lower roller 25, up between the 5 and the upper roller 24, then around the roller 24 up around the roller 29, and then down to the roll 20.

It is the purpose of the rollers 24 and 25 to draw the web from the pad 12 between 10 the pressure bar 26 and blade 27, and it is the purpose of the roller 28' to carry a suitable thinning liquid, such as benzine, from the trough 28 up onto the film of ink on the web as it passes over this roller, while it is 15 the purpose of the roller 29 to cause the web to travel a considerable distance before beginning to wind onto the roll 20, and thus to dry somewhat. While the roller 28' thus applies the thinning liquid to the ink 20 on the web, it applies only such a proportionately small quantity of liquid that the ink will only be softened slightly, to facilitate the action of the removing means comprising the pressure bar 26 and blade 27. 25 This liquid-applying means does not remove any appreciable quantity of ink while thus only softening it, so that substantially the entire quantity of ink that was removed 30 from the die is acted upon and recovered by the ink-recovering means. In practice, only such a minute proportion of the ink is disturbed by the liquid-applying means that the thinning liquid in the trough 28 acquires, after continued operation with the roller 28' 35 coming in contact with the film of ink, only a very slight tint. This operation of the liquid-applying means is in conformity with its function of only slightly softening the ink on the web, and of avoiding wash- 40 ing any appreciable amount of the ink from the web; since it is the purpose of our device to recover the ink ready for use without the necessity of any subsequent operation of evaporating or filtering or similar treatment 45 to reduce the proportion of this liquid in the recovered ink, as would be the case were any washing operation to be permitted in the process of recovering the ink. In fact, the ink would be considerably deteriorated 50 as a result of having thus been diluted, even though the superfluous thinning liquid had been removed as a final operation of the recovering process. The thinning liquid itself, after long continued use, may be fil- 55 tered or similarly treated, and the extremely small amount of ink contained therein, tinting it as above noted, may thus be removed; but if this is done, it will not be done for the value of the ink contained in the thin- 60 ning liquid, since this is of a negligible amount; but will be for the purpose of rendering the thinning liquid better suited for use again.

The rollers 24 and 25 have gears 30 and 65 31, respectively, fixed upon them and mesh-

ing together, while the upper roller has, outside its bearing in the housing 22, a clutch 32 with a sprocket wheel 33. The roller 17 that intermittently moves the web inside the press has a sprocket wheel 34, 70 and a sprocket chain 35 passes around the sprocket wheels 33 and 34, so that the roller 17 drives the upper roller 24 and, through it, the lower roller 25. Preferably, the roller 28' has a pulley 36 turning with it outside its bearing in the housing 22, and the lower stretch of the sprocket chain 35 passes under this pulley to turn the roller 28' at each intermittent turning of the rollers 24 and 25, so that the web 80 need not be depended upon to turn this roller 28'.

The sprocket wheels 33 and 34 are so proportioned that the rollers 24 and 25 will have as nearly as possible the same surface 85 speed as has the roller 17, so that these rollers 24 and 25 will draw the web away from the pad 12 at the same speed that the web is fed to the pad by the rollers 17 and 18, thus avoiding any undue slack or excessive tension on the stretch of web between the pad 12 and these rollers 24 and 25. The roll 20 is intermittently turned by suitable mechanism 37, so that the web is taken up on the roll 20 as fast as it is delivered from the rollers 24 and 25. 90

Notwithstanding the above precautions in design, it is found in practice that it is not always possible to cause the rollers 24 and 25 to have nearly enough the same surface speed as that of the roller 17 to entirely avoid slack or excessive tension on the web, especially after continued operation of the device on the press. We obviate all difficulty that would ensue from such inaccuracy of operation by means of the clutch 32 hereinbefore referred to. The clutch 32, as here shown, and as best illustrated in Figs. 16 and 17, comprises the hub 38 turning with the sprocket wheel 33, and the member 39 with serrated periphery 40, turning with the shaft 41 of the upper roller 24. The sprocket wheel 33 is loose on a reduced end part 42 of the shaft 41, and is held thereon by a washer 43 and screw 44. The hub 38 has radially inwardly extending bores 45 in which are balls 46 bearing against the serrated periphery 40 of the member 39 and held inward thereagainst by helical springs 47, between which and the balls 46 are interposed shoes 48 in the bores 45, and having concave ends to receive the balls and permit the balls to turn easily while thus held against the serrated periphery. The springs 47 are held in the bores by plugs 49 screwed into enlarged outer ends of the bores 45. 110 115 120 125

With the clutch 32 thus constructed, the rollers 24 and 25 may be of such diameter that their inaccuracy is in the direction of 130

being too large, so that they draw the web through the device faster than the rollers 17 and 18 supply it to the pad 12, thus producing an excess of tension on the web, whereupon the helical springs 47 will yield and allow the balls 46 to ride up over the high parts of the serrated periphery 40 to the next serrations thereof, thus allowing the rollers 24 and 25 to remain stationary for the instant, and thus allowing the rollers 17 and 18 of the press to advance with respect to the rollers 24 and 25 and thereby relieve the excessive tension on the web.

The roller 24 is preferably constructed of a tube 50, in the ends of which are plugs 51 and 52, the plug 51 having, integral therewith, the shaft 41 before mentioned as having the member 39 fixed upon it, and it is to this shaft 41 that the gear 30 is fixed. The other plug 52 has the short shaft 53 bearing in the housing 21.

The lower roller 25 is preferably composed of the tube 54, in the ends of which are plugs 55 and 56, the gear 31 being fixed on a reduced part of the plug 55. A longitudinal rod 57 passes through the plugs 55 and 56, and has eccentric bushings 58 and 59 in the housings 21 and 22, respectively. The eccentric bushing 59 is secured to this rod by a pin 60 passing diametrically through the bushing and rod. The bushing 58 has a head 61 outside the housing 21, and is secured to the rod 57 by a screw 62 passing through the head into the rod. This head 61 has a radial handle 63 by means of which the bushing may be turned and thereby turn the rod 57 and the other bushing 59 in the housing 22, to move the roller 25 up toward or down from the upper roller 24, since the roller 25 is journaled on the rod 57 by means of the plugs 56. By means of this eccentric mounting, the lower roller may be drawn away from the upper roller for passing the end of the web between the rollers in applying the web to the machine, and then the lower roller may be brought up tight against the upper roller, with the gears 30 and 31 properly meshing so that the rollers will grip the web and draw it through as before described.

For yieldably supporting the lower roller against the upper roller in conjunction with the eccentric mounting, helical springs 64 are mounted in recesses extending up into the lower ends of the housings 21 and 22 against shoes 65 that bear against the eccentric bushings 58 and 59, while below the springs 64 are plugs 66 screwed up into the openings more or less, to adjust the pressure of the springs 64, through the shoes 65, against the bushings 58 and 59. This yieldable mounting allows the rollers to press the web very tightly and yet permits the lower one to yield to any slight unevenness on the web.

As before stated, the pressure bar 26 is mounted immediately forward of the rollers 24 and 25, having its ends supported on depressed portions of the housings 21 and 22 between the parts of the housings carrying the rollers 24 and 25 and the parts forming the clamps by means of which they are secured to the cross bar 23 as before alluded to. The lower side of the pressure bar 26 is preferably made convex as shown, with a strip of padding material 67, such as felt, passed thereunder between it and the web and blade 27, to protect the web against breaking or tearing as it is drawn under the pressure bar. Preferably, a thin flat strip 68 is interposed between the padding 67 and the convex lower side of the pressure bar 26 immediately forward of the blade 27, so that the padding 67 has a slight backwardly and downwardly directed offset or shoulder, 85 along forwardly of the edge of the blade 27, that causes the web to travel slightly downward and then upward over the edge of the blade, increasing the efficiency of action of the blade thereon.

In the example shown in Figs. 5 to 8, inclusive, a stretcher bar 69 is laid over the top of the pressure bar, while the pressure bar is provided with a pair of upwardly projected lugs 70 near each end between which the stretcher bar 69 has a projection 71 at each end. These lugs 70 thus form vertical guides for the stretcher bar 69; and passing downwardly through the stretcher bar, against the upper side of the pressure bar, are screws 72 which will raise the stretcher bar away from the top of the pressure bar. Extending upward from the top of the stretcher bar are pins 73 arranged in two parallel rows near the sides of the bar, and the strip of padding 67 has openings, preferably provided with eyelets 74, along opposite edges, so that, when the strip is folded around the pressure bar with its edges over the upper sides of the stretcher bar, the pins enter the openings and form engaging means between the stretcher bar and the padding, whereby when the stretcher bar is raised by means of the screws 72 the strip of padding will be tightly stretched around the pressure bar.

The housing 22 has a lug 75, and the middle of the end of the pressure bar 26 is cut out to receive the lug 75, with parts flanking the lug. These flanking parts have slots 76 cut down into them from the top, while their lower outer corners are rounded, and a pin 77 passes transversely through the lug 75 and is received into the slots 76, so that the pressure bar 26 may hinge on this pin, 125 the roundness of the lower corners of the flanking parts permitting the upward swinging of the bar. When the bar has been swung to a vertical position, its end may be slid inward, disengaging it from the 130

pin 77 and allowing it to be removed bodily from the device. The other housing 21 has a lug 78, and the middle part of this end of the pressure bar 26 is cut away to receive 5 this lug, with parts flanking the lug, while a latch screw 79 is screwed down into the lug 78, the head being elongated and adapted to occupy a transverse position and thus engage over the flanking parts of the pressure 10 bar and hold this end of said bar down; when this latch screw 79 is turned through a quarter of a revolution, it will lie longitudinally of the pressure bar, and the cut-away middle part is of such length that the 15 head of the latch screw may not now engage the pressure bar, but will allow it to swing upward at its hinge at the other end, as above described. This upward swinging of the pressure bar is provided for to facilitate the 20 passing of the web over the blade 27 to the rollers 24 and 25, the pressure bar being swung down after the web has been fully threaded through the device, and then pressing 25 the web properly against the edge of the blade.

In the modification shown in Figs. 9, 10 and 11, there is a modified stretcher bar 69' which is confined to one side of the pressure bar 26' and has an upwardly projecting lug 30 80 near each end adapted to come in alignment with a corresponding lug 81 near each end of the pressure bar, and near the front edge thereof screws 72' pass horizontally through the lugs 81 and into the lugs 80 on the stretcher bar 69' to draw the stretcher bar 35 over forwardly of the pressure bar. The stretcher bar is guided in this forward movement by guides 82 fixed to the pressure bar and lapping over reduced end parts of the 40 stretcher bar. This stretcher bar 69' has a row of pins 73' which preferably are slightly inclined forwardly, while the pressure bar itself has a row of pins 73'' projecting from its forward side and preferably slightly inclined 45 upwardly. The pins of these two rows are received in the openings of the padding 67' in the same manner as the pins in the previous example. It will be seen that when the stretcher bar is drawn forward 50 by the screws 72', the padding will be stretched around the lower side of the pressure bar.

The blade may be simply an elongated strip 27^a having its upper edge beveled, as 55 shown in Fig. 4. Preferably, however, a blade 27 of reduced cross section is provided, as best seen in Fig. 3, which is more readily hardened, and this is mounted in a bar 27' which need not be hardened. It is 60 desirable that the blade be held very rigid in order to maintain as nearly as possible a straight line of scraping on the web, but at the same time it is not desirable that the blade 27 or its bar 27' be very deep because, 65 if it is, the ink scraped from the web will

not readily run down off the blade. This blade bar 27', or if used, the blade 27^a, is mounted in short vertical slots 83 in the inner sides of the housings 21 and 22, below the depressed parts where the pressure bar 70 is mounted; and below these slots 83 the 75 housings have inwardly projected ribs 84, up through which pass screws 85, bearing against the lower sides of the ends of the blade bar or blade to adjust it up toward the pressure bar. Passing inwardly through the 80 housings 21 and 22 are clamping screws 86, which may bear firmly against the ends of the blade bar or the blade and hold it in its position as adjusted by the screws 85.

While the blade is thus made adjustable, it may, under some conditions, be desirable to also adjust the pressure bar to the blade; and this we may provide for by inserting an additional thin strip 87 on the convex lower 85 side of the pressure bar between it and the padding 67 and strip 68, as is best seen in Figs. 12 and 13. Passing down through the pressure bar are screws 88 which bear against the upper side of the flat strip 87 90 which, being flexible, will yield in different parts of its length to the particular adjustment of the screw in that region, and therefore the strip 87 and consequently the padding 67 thereunder, may be adjusted differently in different parts of its length along the blade 27. When this means is provided in connection with the modified pressure bar shown in Figs. 9 and 10, the stretcher bar 69^a 95 may be made narrow enough to allow space for the passage of the screws 88 down through the pressure bar. Where it is provided in connection with the stretcher bar lying entirely over the top of the pressure bar, as shown in Figs. 5 to 8, inclusive, the 100 stretcher bar may have openings which permit the screws 88 to pass down through the pressure bar as shown in Figs. 13 and 14.

To catch the ink from the blade 27 and pass it back to the reservoir of the press, the 110 device may be provided with a chute 89, hung on pins 90 projecting inward from the inward sides of the housings. It may, at times, be desirable not to have the recovered ink returned directly to the reservoir; and, 115 for this purpose, the chute 89 may be replaced by a suitable bucket 91 which is hung on the pins 90 and on pins 92 also on the inner sides of the housings farther forward.

To supply a thin liquid, such as benzine, 120 to the trough 28, for the roller 28', a tank 93 may be mounted on the press above the device, and a suitable connection 94 may be provided, as shown in Fig. 2, through which the liquid will pass, drop by drop or in a 125 very slow stream, into the trough 28; this connection being fixed to the trough by entering a lug 95 at the end of the trough adjacent to the housing 21. This drip connection 94 may be adjusted by means of a 130

valve 96 so that the thinning liquid will be supplied only as fast as it is taken up by the roller 29 at each intermittent revolution; but to dispose of the surplus liquid that may collect in the trough when the press is stopped, as is necessary frequently while working with the press, a connection 97 leads from the outlet 97' in the side of the trough forward and outward through an opening in the press frame into a suitable vessel 98 mounted on a bracket 99 on the outside of the press frame, as shown in Fig. 2. This vessel 98 may be emptied from time to time as it fills up, and the liquid which has run into it will still be fit for use. The opening 97" in the bottom of the trough permits emptying the trough for cleaning it.

In some cases it may be desirable to provide one of the rollers 24 or 25 with a ratchet device to resist forward movement of the web 14 under the wiping action as the die 1 passes under the pad 12. Thus, as best seen in Figs. 5, 6 and 8, the end of the upper roller 24 has the friction ratchet wheel 100 and a shell 101 is fixed inside of the housing 21 around the shaft 53, containing small rollers 102 to engage with the teeth of the ratchet wheel 100 and the interior of the shell. The press generally has a ratchet mechanism controlling the roll that takes up the web, and in most instances, this ratchet mechanism may be depended upon to resist the aforesaid forward movement of the web, but in some cases, the increased travel of the web from the pad 12 to the roll 20 may necessitate the ratchet mechanism on one of the actuating rollers of the recovering device, as above alluded to.

It will be seen that where the web passes around the upper roller 24, its surface coming in contact with this roller is the one from which ink has been recovered. It will be understood that our improved device as now set forth recovers such a large percentage of the ink that the amount which is not recovered is insignificant economically, but nevertheless such small amount as does remain upon the web after recovery is sufficient to cause an accumulation of ink upon the surface of the upper roller 24 after continued operation of the device. To prevent this accumulation, we provide a strip 103 of suitable absorbent material, such as felt, to bear on the surface of this roller and saturate this strip with oil which will be applied to the surface in a very thin film and is found to prevent the accumulation of the ink on the roller. This strip 103 is held between two pieces 104 and 105 of angular cross section that extend across from one housing to the other and are fixed thereto, these pieces preferably extending far enough down to form a guard that will prevent accidental entrance of anything between the rollers 24 and 25, such as the fingers of the

operator. The gears 30 and 31 are provided with a guard 106.

By providing the recovering device with the driving rollers 24 and 25 operated directly by the driving rollers of the press, the web is positively drawn across the blade with such force that the blade and pressure bar may have very close adjustment, and by supplementing this with the thinning liquid from the trough 28, applied by the roller 29, almost all of the ink may be recovered from the web without injuring the web and without adulterating the ink by any fibers or any other material scraped from the web. Also, since the device has the driving rollers and the blade and pressure bar all mounted in the same housing, and thus bearing a fixed relation to each other regardless of the position of the device on the press, and regardless of the size of the roll 20 which is receiving the web from the device, there is no variation in the angle at which the web passes from the blade 27; and with the moistening roller 29 provided forwardly, the angle at which the web approaches the pressure bar is always uniform. Therefore, the tendency to break or tear the web by drawing it around the pressure bar or around the blade is minimized.

We have so improved the operation of ink recovering devices that not only is it possible to recover nearly all of the ink from the web as before alluded to, but it also makes it possible to use the web a second time by applying its other side to the wiping of the die; the slight trace of ink remaining on the used side not interfering with the accurate operation of the web through the press, as would be the case were there any considerable amount of ink left on this used side of the web and it were attempted to use the other side of the web. There is, therefore, not only a great saving in ink, but also a great saving in the material used for the web. The benzin or other thinning liquid used, while facilitating the removal of the ink from the web, also is useful in giving the recovered ink a proper consistency for being used again; since the ink in its passage through the press, and during the time it has been upon the web, has dried considerably, and would thus be unsuitable for many kinds of work were it not thinned by benzin or some similar liquid. As hereinbefore set forth, however, the application of this thinning liquid by the liquid-applying means comprising the roller 28' and trough 28 is very closely regulated so as not to thin the ink too much.

Having fully described our invention, what we claim as new and desire to secure by Letters Patent is:

1. In combination with means for making an impression, from which means a portion

6
of ink must be removed before the impression is made, means for removing this portion of ink, and means for actuating this removing means, ink-recovering means actuating upon the removing means, additional actuating means for the removing means adjacent to the ink-recovering means, and operative connection from the aforesaid actuating means to this additional actuating means.

5 2. In combination with means for making an impression, from which means a portion of ink must be removed before the impression is made, a terminable web, actuating means for applying successive lengths of the web to remove successive portions of ink from the impression-making means and comprising a reel for said web, means bearing against the web to recover ink therefrom, actuating means for the web additional to the aforesaid actuating means and adjacent to the means that bears against the web, and operative connection between the aforesaid actuating means and this latter actuating means.

15 3. In combination with means for making an impression, said means having a smooth surface with a depression therein from which smooth surface all of the ink must be removed before the impression is made, and means for removing and carrying away, as a film, all of this ink from this surface, ink-recovering means acting upon said removing means to recover said film of ink, and means 20 for applying liquid to but conserving said film of ink on said ink-removing means before it is removed by said ink-recovering means.

25 4. In combination with means for making an impression, said means having a smooth surface with a depression therein, from which smooth surface all of the ink must be removed before the impression is made, and means for removing and carrying away, as a film, all of this ink from this surface, ink-recovering means acting upon said removing means to recover said film of ink, means for applying liquid to but conserving said film of ink on said ink-removing means before it is removed by said ink-recovering means, and means receiving the recovered ink from said ink-recovering means separate and distinct from said means for applying liquid.

30 5. In combination with means for making an impression, said means having a smooth surface with a depression therein, from which smooth surface all of the ink must be removed before the impression is made, means supplying ink to said smooth surface and said depression, and means for removing all of the ink from said smooth surface, ink-recovering means acting upon said removing means to recover the ink from said removing means and deliver it to said means for ap-

plying ink to said smooth surface and said depression, and means for applying liquid to said ink-removing means before it is acted upon by said ink-recovering means.

5 6. In combination with means for making an impression, said means having a smooth surface with a depression therein from which smooth surface all of the ink must be removed before the impression is made, and means for removing all of this ink from this surface, means for actuating this removing means, ink-recovering means acting upon said removing means, additional actuating means for the removing means adjacent to the ink-recovering means, operative connection from the aforesaid actuating means to this additional actuating means, and means for applying liquid to said ink-removing means before it is acted upon by said ink-recovering means.

10 7. In combination with means for making an impression, said means having a smooth surface with a depression therein from which smooth surface all of the ink must be removed before the impression is made, means for removing all of this ink from this surface, and means for actuating this removing means, ink-recovering means acting upon said removing means, actuatable means for applying liquid to said ink-removing means before it is acted upon by said ink-recovering means, and operative connection from the means for actuating the removing means to said means for applying liquid.

15 8. In combination with means for making an impression, said means having a smooth surface with a depression therein from which smooth surface all of the ink must be removed before the impression is made, means for removing all of this ink from this surface, and means for actuating this removing means, ink-recovering means acting upon said removing means, actuatable means for applying liquid to said ink-removing means before it is acted upon by said ink-recovering means, additional actuating means adjacent to said ink-recovering means, and operative connection from the aforesaid actuating means to this additional actuating means and to said means for applying liquid.

20 9. In combination with means for making an impression, from which means a portion of ink must be removed before the impression is made, a web, and means for applying successive lengths of the web to remove successive portions of ink from the impression-making means, means bearing against the web to recover ink therefrom, means supporting the web for the recovering means to bear thereon, rollers at one side of the bearing means and supporting means between which the web passes and by means of which it is drawn between the bearing means and

supporting means, and a roller at the other side of the bearing means and supporting means, applying liquid to the web.

10. In combination with means for making an impression, said means having a smooth surface with a depression therein from which smooth surface all of the ink must be removed before the impression is made, and means for removing all of this ink from this surface consisting of a terminable web, actuating means for applying successive lengths of the web to remove all of the ink from said smooth surface after each application of ink thereto, means bearing against the web to recover ink therefrom, additional actuating means for the web adjacent to the means that bears against the web, operative connection from the aforesaid actuating means to this additional actuating means, and means for applying liquid to successive portions of the web before they reach the means that recovers the ink therefrom.

11. In combination with means for making an impression, said means having a smooth surface with a depression therein from which smooth surface all of the ink must be removed before the impression is made, and means for removing all of this ink from this surface consisting of a terminable web, actuating means for applying successive lengths of the web to remove all of the ink from said smooth surface after each application of ink thereto, means bearing against the web to recover ink therefrom, additional actuating means for the web adjacent to the means that bears against the web, operative connection from the aforesaid actuating means to this additional actuating means, means for applying liquid to successive portions of the web before they reach the means that recovers the ink therefrom, said additional actuating means being at one side, and said means for applying liquid being at the other side of said means that bears against the web to recover ink therefrom.

12. In combination with means for making an impression, from which means a portion of ink must be removed before the impression is made, a web, and means for applying successive lengths of the web to remove successive portions of ink from the impression-making means, means bearing against the web to recover ink therefrom, a roller bearing against the web to apply liquid to successive portions of the web before they reach the bearing means, a trough in which the roller turns, and means for supplying liquid to the trough.

13. In combination with means for making an impression, from which means a portion of ink must be removed before the impression is made, a web, and means for applying successive lengths of the web to re-

move successive portions of ink from the impression-making means, means bearing against the web to recover ink therefrom, a roller bearing against the web to apply liquid to successive portions of the web before they reach the bearing means, a trough in which the roller turns, means for supplying liquid to the trough, and means for disposing of the liquid from the trough during periods when successive lengths of the web are not being applied and when said roller is not applying said liquid to said web, whereby the supply of liquid to the trough may be continuous, regardless of the starting or stopping of the impression-making means.

14. In combination with means for making an impression, from which means a portion of ink must be removed before the impression is made, a web, and means for applying successive lengths of the web to remove successive portions of ink from the impression-making means, means bearing against the web to recover ink therefrom, rollers adjacent to the bearing means, between which the web passes and by means of which it is drawn past the bearing means, driving means for one of the rollers, and eccentric bushings supporting the other roller, whereby it may be drawn away from the roller having the driving means.

15. In combination with means for making an impression, from which means a portion of ink must be removed before the impression is made, a web, and means for applying successive lengths of the web to remove successive portions of ink from the impression-making means, means bearing against the web to recover ink therefrom, rollers adjacent to the bearing means, between which the web passes and by means of which it is drawn past the bearing means, driving means for one of the rollers, eccentric bushings supporting the other roller, whereby it may be drawn away from the roller having the driving means, and yieldable supports for the eccentric bushings.

16. In combination with means for making an impression, from which means a portion of ink must be removed before the impression is made, means for removing this portion of ink, and means for actuating this removing means, ink-recovering means acting upon the removing means, additional actuating means for the removing means adjacent to the ink-recovering means, and yieldable operative connection from the aforesaid actuating means to this additional latter actuating means.

17. In combination with means for making an impression, from which means a portion of ink must be removed before the impression is made, a web, actuating means for applying successive lengths of the web to remove successive portions of ink from the

impression-making means, means bearing against the web to recover ink therefrom, additional actuating means for the web adjacent to the means that bears against the web, and yieldable operative connection between the means for applying successive lengths of the web and this additional actuating means.

18. In combination with means for making an impression, from which means a portion of ink must be removed before the impression is made, a web, and means for applying successive lengths of the web to remove successive portions of ink from the impression-making means, means bearing against the web to recover ink therefrom, rollers adjacent to the bearing means between which the web passes and by means of which it is drawn past the bearing means, the aforesaid means for applying successive lengths of the web comprising a roller, a sprocket wheel turning with this roller, a yieldable clutch and a sprocket wheel, said yieldable clutch operatively connecting this sprocket wheel to one of the rollers adjacent to the bearing means, and a sprocket chain passing around this sprocket wheel and around the roller comprised in the aforesaid means for applying successive lengths of the web, eccentric bushings supporting the other roller, whereby it may be drawn away from the roller having the clutch and sprocket wheel, and yieldable supports for the eccentric bushings.

19. In combination with means for making an impression, from which means a portion of ink must be removed before the impression is made, a web, and means for applying successive lengths of the web to remove successive portions of ink from the impression-making means, means bearing against the web to recover ink therefrom, rollers adjacent to the bearing means between

which the web passes and by means of which it is drawn past the bearing means, the aforesaid means for applying successive lengths of the web comprising a roller, a sprocket wheel turning with this roller, a yieldable clutch and a sprocket wheel, said yieldable clutch operatively connecting this sprocket wheel to one of the rollers adjacent to the bearing means, a sprocket chain passing around this sprocket wheel and around the roller comprised in the aforesaid means for applying successive lengths of the web, and eccentric bushings supporting the other roller, whereby it may be drawn away from the roller having the clutch and sprocket wheel.

20. In combination with means for making an impression, from which means a portion of ink must be removed before the impression is made, a web, and means for applying successive lengths of the web to remove successive portions of ink from the impression-making means, means bearing against the web to recover ink therefrom, rollers adjacent to the bearing means between which the web passes and by means of which it is

drawn past the bearing means, the aforesaid means for applying successive lengths of the web comprising a roller, a sprocket wheel turning with this roller, a yieldable clutch and a sprocket wheel, said yieldable clutch operatively connecting this sprocket wheel to one of the rollers adjacent to the bearing means, a sprocket chain passing around this sprocket wheel and around the roller comprised in the aforesaid means for applying successive lengths of the web, eccentric bushings supporting the other roller, whereby it may be drawn away from the roller having the clutch and sprocket wheel, and yieldable supports for the eccentric bushings.

21. In combination with means for making an impression, from which means a portion of ink must be removed before the impression is made, a web, and means for applying successive lengths of the web to remove successive portions of ink from the impression-making means, means positively bearing against the web to recover ink therefrom, and a pressure bar positively supporting the web for the recovering means to bear on the web, said pressure bar comprising a hinge, whereby it may be raised from its positively supporting position to release said web from the bearing means, and said hinge being disconnectible only when raised, to permit the pressure bar to be removed bodily from the device.

22. In combination with means for making an impression; from which means a portion of ink must be removed before the impression is made, a web, and means for applying successive lengths of the web to remove successive portions of ink from the impression-making means, means bearing against the web to recover ink therefrom, and a pressure bar supporting the web for the recovering means to bear on the web, a disconnectible hinge under one end of the pressure bar, and a latch at the other end of the pressure bar, said pressure bar when released by the latch being adapted to be raised and release said web from the bearing means, and the disconnectible hinge permitting said pressure bar when raised to be removed bodily from the device.

23. In combination with means for making an impression, from which means a portion of ink must be removed before the impression is made, a web, and means for applying successive lengths of the web to remove successive portions of ink from the impression-making means, means bearing against the web to recover ink therefrom, and a bar supporting the web for the recovering means to bear on the web, means for adjusting the bearing means toward or away from the web, a flexible pressure adjusting strip interposed between the pressure bar and the web, and means for variably ad-

justing different intervals of length of said strip to variously adjust different intervals of the length of the web where the bearing means bears on the web.

24. In combination with means for making an impression, from which means a portion of ink must be removed before the impression is made, a web, and means for applying successive lengths of the web to remove successive portions of ink from the impression-making means, means bearing against the web to recover ink therefrom, a pressure bar supporting the web for the recovering means to bear on the web, a pad interposed between the pressure bar and the web to minimize the disruptive action of the pressure bar on the web, a stretcher bar mounted on the pressure bar, and means connecting the pad to the stretcher bar to stretch said pad across the pressure bar between it and the web.

25. In combination with means for making an impression, from which means a portion of ink must be removed before the impression is made, a web, and means for applying successive lengths of the web to remove successive portions of ink from the impression-making means, means bearing against the web to recover ink therefrom, a pressure bar supporting the web for the recovering means to bear on the web, a pad interposed between the pressure bar and the web to minimize the disruptive action of the pressure bar on the web, a stretcher bar mounted on the pressure bar, means connecting the pad to the stretcher bar to stretch said pad across the pressure bar between it and the web, said stretcher bar having projections on its ends, lugs on said pressure bar between which said projections are guided, and screws passing through the stretcher bar and engaging with the pressure bar to move the stretcher bar away from the pressure bar and stretch said pad as aforesaid.

26. In combination with means for making an impression, from which means a portion of ink must be removed before the impression is made, a web, and means for applying successive lengths of the web to remove successive portions of ink from the impression-making means, means bearing against the web to recover ink therefrom, means for supporting this bearing means, a chute removably mounted upon the supporting means to catch and deliver ink from said blade, whereby it is interchangeable upon said supporting means with a bucket to catch and retain ink from said blade.

27. In combination with means for making an impression, from which means a portion of ink must be removed before the impression is made, a web, and means for applying successive lengths of the web to remove successive portions of ink from the impression-making means, means bearing

against the web to recover ink therefrom, actuating means for the web at one side of the bearing means, means for supplying liquid to the web at the other side of the bearing means, a roll upon which the web is wound after passing from the actuating means, and means around which the web passes from the actuating means to the roll, said means being a considerable distance from the actuating means and said roll, whereby the travel of the web is increased to allow it to dry.

28. In combination with means for making an impression, from which means a portion of ink must be removed before the impression is made, a web, and means for applying successive lengths of the web to remove successive portions of ink from the impression-making means, means bearing against the web to recover ink therefrom, rollers adjacent to the bearing means, between which the web passes and by means of which it is drawn past the bearing means, driving means for one of the rollers, and frictional ratchet means for one of the rollers, preventing return of the web past the bearing means during the coaction between the web and the impression-making means.

29. In combination with means for making an impression, from which means a portion of ink must be removed before the impression is made, a web, and means for applying successive lengths of the web to remove successive portions of ink from the impression-making means, actuating means for the web, to which the web travels from the means applying it to the impression-making means, and means for driving these actuating means, having interposed therein a yieldable clutch comprising concentrically rotatable members, one of which has a serrated periphery, and the other of which has a space communicating with said periphery, an element yieldably held in said space to enter successive serrations of the periphery, and yieldable supporting means for this element, holding it in a serration, but allowing it to ride up over the high parts of the serrated periphery to the next serration thereof, to relieve excessive tension on the web as actuated by the actuating means.

30. An ink saving attachment for embossing presses, including a trough containing a solvent, distributing means feeding the solvent from the trough to the ink wiping strip so as to soften the ink thereon, a pad arranged upon one side of the ink wiping strip, a scraper arranged upon the opposite side of the ink wiping strip and coöperating with the pad to remove the previously softened ink therefrom, and means for collecting the ink removed from the strip by the scraper.

31. An ink saving attachment for embossing presses, including a transverse bar

arranged upon one side of the ink wiping strip, a felt strip extending across the face of the transverse bar, means for drawing the felt strip tightly across the face of the transverse bar, a scraping blade arranged upon the opposite side of the ink wiping strip and coöperating with the transverse bar to recover the ink from the strip, means for

adding a solvent to the ink, and means for collecting the ink removed from the strip by 10 the scraping blade.
